COIN CONTROLLED MECHANISM

Application filed February 23, 1929. Serial No. 341,952.

This invention relates to a coin controlled mechanism for vending machines.

Experience in actual operation of vending machines has shown that they get out of order owing to hard usage by the public and that it is frequently necessary to repair and replace the coin controlled mechanism. Therefore, one object of the invention is to provide an extremely simple form of construction mounted entirely on one removable plate which may readily be attached to the front wall of a vending machine casing.

Further experience with vending machines has shown that the public will attempt to use improper coins, as well as slugs and washers. The present invention is intended for use with coins of a non-magnetic character and the broad, general object of the invention is to provide a simple construction which cannot be operated by an improper coin or by a slug or washer and that when an improper coin, slug or washer is inserted, goods will not be delivered and such coin, slug or washer will be returned.

Experience with vending machines has further shown that when the machine is empty and customers insert coins the customer becomes exasperated and frequently injures the machine, so that one of the objects of the invention is to provide a means for automatically indicating when the machine is empty of goods and for automatically and positively locking the coin insertion opening so that a coin cannot be inserted when the vending machine is empty of goods.

Experience has further shown that owing to hard usage coin controlled mechanisms of this type will become jammed or broken. When a coin is inserted under such conditions and not returned, naturally the customer is not satisfied. Therefore, a further object of the invention is to provide a mechanism which will return the coin in the event that the mechanism has become jammed or broken.

For the purposes of quick repair a further object of the invention is to provide a very simple construction, so that the parts are interchangeable and so that the construction may be quickly taken down and reassembled with simple tools.

The invention consists of the construction, combination and arrangement of parts, as herein illustrated, described and claimed.

In the accompanying drawings, forming part hereof, is illustrated one form of embodiment of the invention, in which drawings similar reference characters designate corresponding parts and in which:

Figure 1 is a rear elevation, partly broken away;

Figure 2 is a vertical section taken approximately on line 2—2 of Figure 1, looking in the direction indicated by the arrows;

Figure 3 is a fragmentary detail in vertical section, taken approximately on line 2—2 of Figure 1, looking in the direction indicated by the arrows;

Figure 4 is a composite view showing the structure of the operating shaft and collar;

Figure 5 is a fragmentary detail in front elevation;

Figure 6 is a fragmentary detail in vertical section, taken approximately on line 2—2 of Figure 1, looking in the direction indicated by the arrows, showing the washer detector engaged by a washer;

Figure 7 is a fragmentary detail in vertical section, taken approximately on line 2—2 of Figure 1, looking in the direction indicated by the arrows, showing the washer detector as a washer is being released;

Figure 8 is a fragmentary detail in vertical section, taken approximately on line 2—2 of Figure 1, looking in the direction indicated by the arrows, showing the slug detecting means holding a slug; and,

Figure 9 is a fragmentary detail in vertical section, taken approximately on line 2—2 of Figure 1, looking in the direction indicated by the arrows, showing the slug detecting means in the position occupied as a slug is released.

Referring to the drawings A designates a portion of the front wall of a vending machine having an opening therein. Disposed in the opening in the wall A is a supporting panel 12 which carries the entire mechanism hereinafter described. The panel 12 is provided with edge flanges 13. An elongated boss 14 is disposed on the panel 12 near its

60

55

65

70

75

80

85

90

95

100

top. Between one flange 13 and the boss 14 is disposed a rectangular plate 15 rockably carried by a pivot-pin 16 which pin 16 extends through the boss 14 and the flange 13.

5 The plate 15 is provided with strengthening ribs 17. The plate 15 also has a recessed portion 18 near the top for the purpose of receiving and holding an indicating means hereinafter described. Disposed centrally of the 10 plate 15, and at the point where the pin 16 passes through, is an opening 19 so that a plate 20 may be pivoted on the pin 16 between the plate 15 and the panel 12. The plate 20 is provided with an angularly offset portion 20a 15 on the front face thereof, the use of which is hereinafter described.

Disposed between the ribs 17 on the plate 15 is a U shaped magnet 21. The ends 22 of the magnet 21 are bent at an angle of 90° and 20 extend through openings 23 in the plate 15 and also through openings 24 in the plate 20 to the forward face of the plate 20. The purpose of the magnet 21 is to catch and hold any slug or other improper coin which may 25 be inserted in the machine, as hereinafter described.

Between the arms of the magnet 21 is a retaining member 25 having projecting flanges 26 which hold the magnet 21 in position. The 30 retaining member 25 is provided with a recess 27 in which is placed a spiral spring 28. A stud 29 passes through the spring 28, the retaining member 25, the plate 15 and into the second plate 20. Therefore, when the plate 35 15 is actuated as hereinafter described, the spring 28 is compressed and, under tension, moves the stud 29 and the plate 20. A pin 30 in one edge flange 13 of the panel 12 limits the range of movement of the plate 20, (Figure 1).

40 A recess 31 is provided on the front face of the plate 15 near the top thereof. A spiral spring 32 is disposed in the recess 31 and when the plate 15 is actuated the spring 32 is compressed, and tends to return the plate 15 to its normal position. Since the movement of the plate 20 is limited by the pin 30 the spring 28 also exerts pressure on the plate 15, tending to return it to its normal position.

45 The plate 15 is provided with a vertical slot 33 and in alignment therewith is a second vertical slot 34 in the plate 20. Disposed in these slots 33 and 34 is a latch 35 which is pivoted offcenter by a pin 36 through the 50 plate 15. The latch 35 is provided with a projecting shoulder 37 and a hook 38 adapted to intercept washers, as will appear more fully hereinafter.

55 A projecting lug 39 is carried by the plate 15 and lies in the path of movement of the teeth of a serrated eccentric collar 40 on a shaft 41. The shaft 41 projects through the panel 12 and is provided with a handle 42 on its outer end. The inner end of the shaft 41 60 terminates in a bifurcated boss 43 which is

adapted to engage any kind of apparatus which may be operated by rotation of the shaft 41.

A circular boss 44 is disposed on the panel 12. An offset lever 45 is pivoted on the boss 44 and is provided with a flange 46. On the forward face of the lever 45 is a lug 47 which is adapted to act as a coin holder. A second lever 48 is also pivoted on the boss 44 behind the lever 45. The lever 48 has a vertical 75 flange 49 on its forward face in alignment with the lug 47 on the lever 45 so that when a proper coin is inserted it will be held between the lug 47 and the flange 49.

80 Centrally of its length the lever 48 has a shoulder 50. When the mechanism is in normal position the shoulder 50 lies in the path of movement of a recess 51 on the collar 40 on the shaft 41 so that the handle 42 may be turned approximately 20° before the shoulder 50 engages the recess 51 and prevents further movement. When in this position the lever 45 is against the thinnest part of the eccentric collar 40.

85 The levers 45 and 48 are held against the collar 40 by means of a leaf spring 52 which is inserted between the levers 45 and 48 and one edge flange 13 on the panel 12. The upper end 53 of the spring 52 engages a lug 54 on the lever 45 and the lower end 55 of the spring 52 engages in a recess 56 in the lever 48, thus holding both the levers 45 and 48 yieldingly against the collar 40. The lever 45 is in contact with the forward portion of the collar 40, that is, the portion 100 nearest the panel 12 and the lever 48 is in contact with that portion of the collar 40 which is nearer to the bifurcated boss 43. The portion of the collar 40 against which the lever 48 presses is not eccentric. 105

110 A cover plate 57 holds the levers 45 and 48 and the spring 52 in place. The plate 57 is held by means of a stud 58 which passes through the plate 57 and into a boss 59 on the panel 12.

115 On one side of the panel 12 is disposed a coin box 60 which is provided with a hinged door 61. The portion of the coin box 60 which is directly below the lower ends of the levers 45 and 48 is provided with an opening 62, through which the coin may be dropped as hereinafter described.

120 Directly below the plate 20 is disposed a coin return chute 63 which is secured to the side of the coin box 60 by means of flanges 64. The lower end of the return chute 63 communicates with the package delivery chute (not shown) and any unused coins may be returned to the operator.

125 In order to insert coins into the mechanism a coin opening 65 is provided in the panel 12.

An indicating means is provided in order to show when the machine is empty. This indicating means comprises a bar 66 which is 130 rockably held by a pivot 67 to the boss 14 on

the panel 12. Carried by the bar 66 is a flag 68 having thereon the word "Empty" or other indicia to indicate that the machine is empty. On one end of the bar 66 is a projection 69 which lies in the path of movement of a follow-weight in the package chute (not shown, but of construction shown in our copending application, Ser. No. 341,953), so that when the last package is vended the bar 66 and the flag 68 are swung to the dotted line position shown in Figure 1. In order that the flag 68 may be seen from without, a window 70 is provided in a frame 71. The frame 71 is held by studs 72 to the front wall A of the vending machine. When the indicating means is swung to the dotted line position shown in Figure 1, one end of the bar 66 is forced into the recess 18 in the plate 15. This not only tends to hold the bar 66 in a horizontal position but also forces a circular boss 73 on the forward face of the plate 15 into the coin opening 65 (as shown in Figure 3), so that no coin can be inserted in the machine when it is empty.

The flanges 74 on the top of the front wall A and the hook 75 on the bottom thereof are used, in conjunction with other means, to hold the front wall A in position on the machine.

The letters C, W, and S used in the drawings indicate coins, washers and slugs respectively.

OPERATION

(a) *When a proper coin is inserted*

When a proper coin C is inserted in the coin opening 65 it falls in a vertical line in the space between the plates 15 and 20 and the panel 12. The coin C strikes the shoulder 37 of the latch 35 which impedes but does not stop its fall. It therefore continues to fall until it reaches a point adjacent the offset portion 20a of the plate 20. At this point the opening between the plate 20 and the panel 12 is too small to permit further vertical travel. The coin C then rolls down the angular offset portion 20a of the plate 20 (see Figure 5) and is caught and held between the lug 47 on the lever 45 and the flange 49 on the lever 48. The elapsed time necessary for the foregoing action by the coin C is momentary.

The handle 42 is then turned clockwise which rotates the shaft 41. Since the lever 45 is against the thinnest portion of the eccentric collar 40, when the shaft 41 is rotated the lever 45 is forced toward the left hand of Figure 1. The coin C is also forced to the left hand of Figure 1 and carries with it the lever 48 to the dotted line position shown in Figure 1. As the lever 48 is moved the shoulder 50 thereon is moved from the path of movement of the recess 51 on the collar 40 and the shaft 41 is free to rotate. When the shaft 41 has made a full half turn the thickest part of the collar 40 is presented

to the lever 45. As the shaft 41 is rotated still further the lever 45 begins to move back to its original position until it reaches the dotted line position shown in Figure 1. Since the portion of the collar 40 against which the lever 48 is pressed is not eccentric the lever 48 stays in the dotted line position until a full revolution of the collar 40 has been made. Therefore, when the lever 45 reaches the dotted line position the gap between the levers 45 and 48 is large enough to permit the coin C to drop through the opening 62 into the coin box 60. The rotation of the shaft 41 then continues until a full turn has been completed when the shoulder 50 on the lever 48 again engages the detent 51 on the collar 40 and the levers 45 and 48 are in their normal positions. In the meantime, the projection 39 on the plate 15 has ridden over the successive teeth on the collar 40 and has returned to its original position. It will be understood that the rotation of the shaft 41 operates a goods dispensing means which is not shown and which forms no part of this application.

(b) *When a washer is inserted*

When the mechanism is in normal position the latch 35 is in the position shown in Figure 2. If a washer W be inserted in the coin opening 65 it will fall between the plates 15 and 20 and the panel 12. As the washer W falls it will strike the shoulder 37 on the latch 35. This will swing the latch 35 on its pivot 36 to the position shown in Figure 6 and the washer W will be caught on the hook 38 of the latch 35. The shaft 41 is sufficiently free to permit a partial turn of the handle 42, so that the projection 39 on the plate 15 will mount the first tooth on the collar 40. This will cause the plate 15 to move on its pivot 16 and the lower part of the plate 15 will move away from the panel 12. The spring 28 will be compressed and by reason of the pressure on the stud 29 the plate 20 will also move away from the panel 12 but the plate 20 will not move as far as the plate 15 because the pin 30 in the flange 13 stops its progress after it has moved a slight distance. As the plate 15 moves away from the panel 12 the latch 35 will be withdrawn from the slot 34 in the plate 20 and the washer W will be released from the hook 38. As the plate 20 moves away from the panel 12 the distance between the offset portion 20a of the plate 20 and the panel 12 will increase. Therefore, when the washer W is released it will not strike the offset portion 20a of the plate 20 but will fall between the plate 20 and the panel 12 into the coin return chute 63 and will be returned to the outside of the machine.

(c) *When a slug is inserted*

If a slug S or other improper coin is inserted in the coin opening 65 it will fall in a

manner similar to a proper coin C. The progress of the slug S will be impeded by striking the shoulder 37 of the latch 35 but will not be stopped. When the slug S reaches a point adjacent the openings 24 it will be stopped and held by the magnet 21, as shown in Figure 8. When the handle 42 is turned the plates 15 and 20 will move away from the panel 12. Since the pin 30 in the flange 13 will stop the movement of the plate 20, the plate 15 will move further away from the panel 12. This will withdraw the ends 22 of the magnet 21 from the openings 24 in the plate 20 and the slug S will be released. Since the plate 20 is also moved away from the panel 12 the slug S will fall into the coin return chute 63 and will be returned to the outside of the machine.

When the mechanism is in normal position the projection 39 on the plate 15 rests in a recess 76 between two of the teeth on the collar 40. The recess 76 is deeper than the other recesses between the several teeth on the collar 40. If the mechanism becomes jammed, broken or inoperative in any position other than the normal position the projection 39 will either be in one of the recesses between the several teeth on the collar 40 or on top of one of the teeth. If the projection 39 is on top of one of the teeth on the collar 40 the plates 15 and 20 will be in the position shown in Figure 3. The circular boss 73 on the plate 15 will obstruct the coin opening 65 so that no coins may be inserted. If the projection 39 lies in any of the recesses between the teeth of the collar 40 other than the recess 76 the plates 15 and 20 will still be a sufficient distance from the panel 12 to permit any coin which may be inserted in the coin opening 65 to drop through the opening between the offset portion 20a of the plate 20 and the panel 12, so that it will be returned by means of the coin return chute 63.

Having thus fully described the invention what is claimed as new and desired to be secured by Letters Patent, is:

1. A coin controlled mechanism comprising a casing having a coin insertion opening, a pair of pivoted plates disposed in the casing adjacent the wall of the casing and a rockable member carried by one plate, extending through the plates and provided with projecting elements in the path of movement of an object inserted in the opening.

2. A vending apparatus comprising a casing having a coin insertion opening, a pair of pivoted plates pivoted to the casing, one of which is provided with an inclined offset portion adjacent the wall of the casing, means for maintaining the plates in one position and means for rocking the plates away from the wall of the casing.

3. In a coin controlled vending machine an actuating assembly comprising the combina-

tion of a casing, a pair of rockable pivoted plates arranged close to the casing but sufficiently spaced therefrom as to permit the passage of a proper, predetermined coin between the casing and one plate and means when a proper coin is inserted to direct the coin past slug and washer detectors carried by the plates.

4. A coin controlled mechanism comprising a casing having a coin insertion slot, a pair of superposed, pivoted plates disposed within the casing adjacent the slot, an operating shaft provided with a serrated collar to actuate the plates and means carried by the plates to detect and reject washers.

5. A coin controlled mechanism comprising a casing having a coin insertion slot, a pair of superposed, pivoted plates disposed within the casing adjacent the slot, an operating shaft provided with a serrated collar to actuate the plates and means carried by the plates to detect and reject washers, comprising a latch pivoted offcenter in one of the plates and having a projection adapted to be struck by a washer and a hook on the latch adapted to engage a washer and means to withdraw the latch through one of the plates to release the washer.

6. A coin controlled mechanism comprising a casing having a coin insertion slot, a pair of superposed, pivoted plates disposed within the casing adjacent the slot, an operating shaft provided with a serrated collar to actuate the plates and means carried by the plates to detect and reject washers comprising a latch pivoted offcenter in one of the plates, a projecting shoulder on the latch adapted to lie in the path of movement of a washer and a hook on the latch adapted to be swung into the path of movement of a washer to intercept and hold the same and means to withdraw the latch through one of the plates to release the washer.

7. In a vending machine a means for detecting and preventing the use of washers or perforated coins comprising an operating shaft, a serrated collar disposed on the shaft, a rockable plate, a projecting lug on the plate in the path of movement of the serrated collar, a latch pivoted in the plate and having a projecting shoulder in the path of movement of a washer, a hook on the latch to intercept and hold a washer and means to release the washer from the hook and eject it from the machine.

8. In a vending machine a means for detecting and preventing the use of washers or perforated coins comprising an operating shaft, a serrated collar disposed on the shaft, a rockable plate, a projecting lug on the plate in the path of movement of the serrated collar, a latch pivoted in the plate and having a projecting shoulder in the path of movement of a washer, a hook on the latch to intercept and hold a washer and means operable by

the movement of the operating shaft to release a washer from the hook and eject it from the machine.

9. In a coin controlled mechanism a means for detecting and preventing the use of washers or perforated coins comprising an operating shaft, a serrated collar on the shaft, a rockable plate, a lug on the plate in the path of movement of the serrations on the collar, a latch pivoted in a slot in the plate and provided with a hook to intercept and hold a washer, a coin insertion opening above the latch and a guide below the latch and coin opening to return a washer to the outside of the machine.

10. In a coin controlled mechanism a means for detecting and preventing the use of washers or perforated coins comprising an operating shaft, a serrated collar on the shaft, a rockable plate, a lug on the plate in the path of movement of the serrations on the collar, a latch pivoted in a slot in the plate and provided with a hook to intercept and hold a washer, said plate being adapted to be rocked by the movement of the serrated collar to withdraw the latch within the slot and release the washer from the hook, a coin insertion opening above the latch and a guide below the latch and coin opening to return a washer to the outside of the machine.

11. A coin controlled mechanism comprising a casing having a coin insertion slot, a pair of superposed, pivoted plates disposed within the casing adjacent the slot, an operating shaft provided with a serrated collar to actuate the plates and means carried by the plates to detect and reject slugs.

12. A coin controlled mechanism comprising a casing having a coin insertion slot, a pair of superposed, pivoted plates disposed within the casing adjacent the slot, an operating shaft provided with a serrated collar to actuate the plates and means carried by the plates to detect and reject slugs comprising a latch to impede the movement of a slug and a magnet to hold the slug from further movement and means to withdraw the magnet to release the slug.

13. A coin controlled mechanism comprising a casing having a coin insertion slot, a pair of superposed, pivoted plates disposed within the casing adjacent the slot, an operating shaft provided with a serrated collar to actuate the plates, a magnet to hold the slug from further movement and means to release the slug from the magnet.

14. A coin controlled mechanism comprising a casing having a coin insertion slot, a pair of superposed, pivoted plates disposed within the casing adjacent the slot, an operating shaft provided with a serrated collar to actuate the plates and means carried by the plates to detect and reject slugs comprising a latch to impede the movement of a slug and a magnet disposed on one of the plates

to hold the slug from further movement, said plates being adapted to be rocked to release the slug from the magnet and eject it from the machine.

15. In a vending machine, a slug detector comprising a pair of pivoted plates, a magnet carried by one plate and extending through openings in the other plate, and means to actuate the plates so as to withdraw the magnet from the second plate to release the slug.

16. A coin controlled mechanism comprising an operating shaft, a serrated collar disposed on the shaft, a pair of pivoted plates one of which has a projecting shoulder in the path of movement of the serrated collar and a magnet disposed on one plate and projecting therethrough and through the second plate, said plates being adapted to be reciprocated by the movement of the operating shaft to eject slugs inserted in the mechanism.

17. In a coin controlled mechanism a fraud preventive assembly comprising a casing having a coin insertion slot therein, a pair of pivoted plates disposed in the casing adjacent the slot, a latch and a magnet on one plate to prevent the use of improper coins, a shoulder on one plate disposed in the path of movement of a collar and an operating shaft provided with a serrated collar to actuate the mechanism.

18. A coin controlled mechanism comprising a casing having a coin insertion opening, a pair of pivoted plates disposed in the casing adjacent the coin opening, said plates being spaced from the casing to allow the passage of a coin, operating means to actuate the mechanism and means carried by one plate to direct the line of travel of a coin inserted in the coin opening.

19. A coin controlled mechanism comprising a casing having a coin insertion opening, a pair of pivoted plates disposed in the casing adjacent the coin opening, said plates being spaced from the casing to allow the passage of a coin, operating means to actuate the mechanism and means carried by one plate to direct the line of travel of a coin inserted in the coin opening comprising an offset portion on one plate disposed in the path of movement of a coin.

20. A coin controlled mechanism comprising a casing having a coin insertion opening, a pair of pivoted plates disposed in the casing adjacent the coin opening, said plates being spaced from the casing to allow the passage of a coin, operating means to actuate the mechanism, means carried by one plate to direct the line of travel of a coin inserted in the coin opening comprising an offset portion on one plate disposed in the path of movement of a coin and means to move the plates and the offset portion out of the path of movement of an improper coin.

21. A coin controlled mechanism comprising

ing a casing having a coin insertion opening, a pair of pivoted plates disposed in the casing adjacent the coin opening, an operating shaft to actuate the plates and means to re-
5 turn coins if the mechanism is out of order.

In testimony whereof they affixed their signatures.

MARSHALL CORNINE.
ALFRED HAKANSON.
